US0D1086972S

(12) **United States Design Patent** (10) **Patent No.:** **US D1,086,972 S**
(45) **Date of Patent:** **** Aug. 5, 2025**

(54) **FOLDING KITCHEN FOR VEHICLE CANOPY**

(71) Applicant: **Rock Solid Industries International (Pty) Ltd**, Pietermaritzburgh (ZA)

(72) Inventor: **Michael Voss**, Pinetown (ZA)

(73) Assignee: **Rock Solid Industries International (Pty) Ltd**, Pietermaritzburgh (ZA)

(**) Term: **15 Years**

(21) Appl. No.: **29/761,468**

(22) Filed: **Dec. 9, 2020**

Related U.S. Application Data

(63) Continuation of application No. 29/681,255, filed on Feb. 22, 2019, now Pat. No. Des. 1,008,928.

(57) **CLAIM**

The ornamental design for a folding kitchen for vehicle canopy as shown and described.

DESCRIPTION

FIG. 1 is a perspective view of a folding kitchen for vehicle canopy of my new design with a tray in a deployed position; FIG. 2 is a perspective view of the folding kitchen for vehicle canopy showing the tray in a partially-folded position;

FIG. 3 is a perspective view of the folding kitchen for vehicle canopy showing the tray in a folded position; and, FIG. 4 is a front elevation view thereof.

The broken lines adjacent to shaded areas depict bounds of the claimed design and depict features of the folding kitchen for vehicle canopy that form no part of the claimed design. All other broken lines depict features of the folding kitchen for vehicle canopy that form no part of the claimed design.

1 Claim, 4 Drawing Sheets
